Primary Examiner—Susan J. Lucas
Attorney, Agent, or Firm—Donald L. Beeson[57] **CLAIM**

The ornamental design for a direct-indirect luminaire housing, as shown and described.

DESCRIPTION

FIG. 1 is a broken away bottom perspective view of a direct-indirect luminaire housing in accordance with our new design;

FIG. 2 is a broken away bottom plan view thereof;

FIG. 3 is a broken away front elevational view thereof, the rear being a mirror image thereof; and,

FIG. 4 is a left side elevational view thereof, the right side being a mirror image thereof.

The figures are broken away to indicate indeterminate length.
